UNITED STATES PATENT OFFICE.

JAY B. RHODES, OF CHICAGO, ILLINOIS, ASSIGNOR TO FREDERICK C. AUSTIN, OF SAME PLACE.

IMPACT-TOOL.

SPECIFICATION forming part of Letters Patent No. 613,311, dated November 1, 1898.

Application filed May 28, 1897. Renewed April 4, 1898. Serial No. 676,479. (No model.)

To all whom it may concern:

Be it known that I, JAY B. RHODES, a citizen of the United States, residing at Chicago, in the county of Cook and State of Illinois, have invented a certain new and useful Improvement in Impact-Tools, of which the following is a specification.

My invention relates in general to rock-drills or other impact-tools adapted for operation by means of steam, compressed air, or other motive fluid under pressure and having a piston-chamber inclosing a piston which carries the drill or other implement, and it relates in particular to a construction of impact-tool in which the piston is reciprocated within its chamber by a valve mechanism operating independently of its movement, and comprising to such end a fluid-actuated reciprocating distribution-valve or "piston-valve," as it may be termed, which by its reciprocation properly distributes motive fluid to the piston-chamber for reciprocating the piston, and a fluid-actuated reciprocating valve which by its reciprocation admits motive fluid alternately to the opposite ends of the piston-valve chamber, so as to reciprocate the piston-valve, and which is reciprocated to such end by motive fluid admitted alternately to the opposite ends of its valve-chamber by the reciprocation of the piston-valve. This construction, embodying, as it does, a valve mechanism operating independent of the piston movement, has heretofore frequently proved unsatisfactory, because the piston has been subjected to a period of admission too short to cause its effective reciprocation—that is to say, the discharge of motive fluid has been alternated from one side of the piston to the other so rapidly as to prevent the latter from moving with any degree of force in either direction. This result has been due to the fact that the motive fluid has been admitted by the piston-valve to the piston-chamber and to the supplemental-valve chamber at the same time and that the supplemental valve has therefore been reversed so quickly that it has caused a premature reversal of the piston-valve and a consequent premature termination of the period of admission of motive fluid to the piston-chamber. The obvia-

tion of this objectionable feature is a prominent object of my invention.

Other objects of the invention are to allow motive fluid to be distributed independently in the piston-chamber and in the valve-chambers, to reduce to a minimum the size of the tool, to protect the supplemental valve from external injury, to arrange for an intermittent twisting or rotating of the drill or other implement without at the same time reducing the effective piston area, to arrange for an effective cushioning of the piston at the ends of its stroke, to allow the piston and valves to be easily, conveniently, and rapidly removed from and replaced within their respective chambers, and to provide certain novel features of construction and arrangement tending to increase the efficiency of such tools and to reduce their cost of manufacture, maintenance, and operation.

In an impact-tool characterized by my invention motive fluid which is admitted alternately to the opposite ends of both the piston-chamber and the supplemental-valve chamber by the piston-valve is admitted to the piston-chamber before it is admitted to the supplemental-valve chamber, and as a preferred arrangement it is admitted to the supplemental-valve chamber only at a time when the piston-valve reaches one or the other of the ends of its stroke. By thus admitting motive fluid to the piston-chamber before it is admitted to the supplemental-valve chamber the piston is given opportunity to acquire momentum enough to strike an effective blow before the supplemental valve is actuated to reverse the direction of motion of the piston-valve, and thereby terminate the period of admission, and by delaying the admission of motive fluid to the supplemental-valve chamber until the piston-valve has reached the end of its stroke the piston-chamber is supplied with motive fluid for the longest possible period of time before the piston-valve is thus reversed by an actuation of the supplemental valve.

In the accompanying drawings, Figure 1 is a side elevation of an impact-tool embodying my invention, certain portions of the same being shown in section. Fig. 2 is a front eleva-

tion of the cylinders which provide the piston-chamber and piston-valve chamber, respectively. Figs. 3 and 4 are horizontal sections taken on lines xx and $x'x'$, respectively, in Fig. 5. Fig. 5 is a vertical section taken centrally through said piston and piston-valve cylinders, showing the piston-valve in elevation. Fig. 6 is a vertical and central section of the middle longitudinal portion of the piston-cylinder on a larger scale. Figs. 7 and 8 are horizontal sections taken on lines yy and $y'y'$, respectively, in Fig. 6. Fig. 9 is a view illustrating, on an enlarged scale, the piston-valve cylinder and the piston-valve in section and the supplemental valve in elevation. Figs. 10, 11, and 12 are horizontal sections taken on lines zz , $z'z'$, and $z''z''$, respectively, in Fig. 9. Fig. 13 is a vertical section similar to that of Fig. 5, illustrating a modified arrangement of the piston and supplemental valves. Fig. 14 is a vertical elevation of the same with the cylinder which provides the supplemental-valve chamber removed therefrom. Fig. 15 is a bottom plan view of said cylinder.

I have shown in the drawings a drill 1, connected by a suitable connection 2 with a piston-rod 3, which latter is reciprocated so as to effect the desired drilling operation by means 30 of a piston arrangement inclosed within a piston-chamber A, which is conveniently provided by a piston-cylinder A'.

The drill 1 is desirably twisted or rotated between its successive blows for the purpose 35 of presenting it in a different position for each blow. To such end either the piston arrangement inclosed within the piston-chamber A for reciprocating such drill or the piston-rod 3, connecting the piston arrangement and the 40 drill, could be constructed in any suitable manner and could be connected in any preferred manner with some suitable device for imparting such intermittent rotation or twisting motion to the drill. As a matter of further improvement, however, the piston arrangement 45 comprises a couple of separated piston-heads B and B' and a connecting-rod 5, which latter is attached at its ends to said piston-heads B and B' and is arranged in engagement with a device whereby it is intermittently twisted or rotated automatically by 50 its own reciprocation, and thereby operates to twist or rotate the drill between the successive blows thereof. By thus arranging 55 the twisting or rotating device intermediate of a couple of separated piston-heads the entire area of the upper face of the upper piston-head is exposed to the motive fluid when the same is admitted to the upper end of the 60 piston-chamber, and the drill therefore is driven downward with the greatest force possible, whereas if such device were situated at the upper end of the piston-chamber and a rod or the like extended upward from the 65 upper piston-head the exposed area of the upper face of such upper piston-head would

be decreased by the cross-sectional area of such rod.

The piston-heads B and B', the piston-rod 3, and the connecting-rod 5 can be conveniently constructed and secured together by forming the piston-rod 3, the lower piston-head B', and the connecting-rod 5 integral with one another and by then screwing the upper piston-head B upon the suitably-threaded upper end portion of the connecting-rod 5, as best shown in Fig. 5, it being observed that said connecting-rod 5 should be of such length with reference to its length of stroke as to allow the piston-heads to reciprocate on either side of the intermediate twisting or rotating device without interfering therewith.

The device inclosed within the piston-chamber and adapted for engaging the connecting-rod 5 for intermittently twisting or rotating the same could be of any suitable construction; but as a preferred arrangement and matter of further improvement such device comprises a couple of collars 7 and 8, inclosing the connecting-rod 5 and provided, respectively, with oppositely-arranged coöperating ratchet-teeth 9, whereby when the teeth 9 are in engagement the collars are locked against relative rotation in one direction, but are free to rotate in the opposite direction.

The upper collar 7 is secured within the piston-chamber against rotary motion and sliding movement longitudinally of said chamber and fits loosely over and is disconnected from the connecting-rod 5, so as to allow the latter to work freely within it. The lower collar 8, on the contrary, fits loosely within the piston-chamber, so as to allow of its being rotated therein and also so as to allow of its being slid longitudinally thereof into and out of engagement with the upper fixed collar 7, and also it engages the connecting-rod 5 by means of a number of inwardly-projecting tongues 10, with which it is provided, and a corresponding number of grooves 11, formed longitudinally in said connecting-rod 5 and adapted to receive the tongues 10, said grooves 11 being so inclined that the connecting-rod 5 tends during its rise to turn the collar 8 in the direction against which it is locked when in engagement with the upper fixed collar 7 and to turn said collar 8 in the opposite direction during its descent; also, the loose collar 8 has a friction connection with the connecting-rod 5—as, for instance, by means of a friction clasp-ring 12, inclosing the connecting-rod and inclosed in turn within a suitable annular chamber formed internally in said collar 8, whereby the latter is slid automatically into and out of engagement with the upper fixed collar 7 by the rise and descent of the connecting-rod 5, and it is provided with a stop adapted to limit its descent when it has been moved downward by the connecting-rod sufficiently to cause it

to become disengaged from the upper fixed collar 7. By such arrangement the lower loose collar 8 is slid automatically upward and into engagement with the upper fixed 5 collar 7 by the initial rise of the connecting-rod 5 and is held there against rotation during the remaining portion of the upstroke of said connecting-rod, thereby causing the latter, and consequently the drill, to turn or rotate, and by the initial descent of the connecting-rod said collar 8 is slid automatically out of engagement with the upper fixed collar 7 and is rotated thereby during the remaining portion of the downstroke, thereby 15 allowing the connecting-rod, and consequently the drill, to descend without rotating.

The collar 7 could be secured against rotation within the piston-chamber and the loose collar 8 could be provided with a stop limiting its downward movement in any suitable manner. As illustrative of arrangements for such purpose I have shown in Figs. 5 to 7, inclusive, both of said collars inclosed within a sleeve 13, the collar 7 being secured tightly 20 therein against movement and the loose collar 8 being fitted loosely therein and the said sleeve 13 being in turn fitted tightly within the bore of the piston-cylinder A' and provided at its lower end with an inwardly-extending annular flange 14, which serves as a 25 stop for limiting the downward movement of the loose collar 8.

In Fig. 13 I have shown the collar 7 itself secured tightly within the bore of the piston-cylinder A', being to such end embedded in an annular recess formed in the latter, and have shown also a disk 15, inclosing the connecting-rod 5 and secured within the bore of the piston-cylinder A', below the loose collar 40 8, for the purpose of limiting the downward movement of the latter.

I have chosen to claim the broader features of the previously-described drill-twisting arrangement and the specific construction illustrated in Figs. 5 to 8, inclusive, in the present application and to claim the specific construction illustrated in Fig. 13 in another application, illustrating the same and filed contemporaneously with the present application.

50 With reference to the relative arrangement of the fixed and loose collars 7 and 8 it will be observed that the positions of the same could be reversed—that is to say, the lower collar could be fixed or stationary within the piston-chamber and the upper collar could be loose therein; but I prefer the arrangement illustrated, chiefly for the reason that in it the connecting-rod 5 is disengaged from all mechanism tending to hold it against rotation during its downstroke, and the drill therefore can turn freely without breaking or injuring itself or other parts of the device, as required by peculiarities or irregularities in the hole being drilled, whereas if the position of said collars was reversed said connecting-rod would be engaged for rotation during its downstroke, and the drill therefore

could not rotate except in accordance with the rotation imparted to it as a result of its descent without injury to itself or some other 70 part of the device.

The valve mechanism, which operates independently of the piston and which causes a reciprocation of the latter by effecting a proper distribution of motive fluid to the piston-chamber A, comprises a reciprocating fluid-actuated cylindrical piston-valve D and a reciprocating fluid-actuated cylindrical supplemental valve E, inclosed, respectively, in suitable valve-chambers D' and E'. The 75 piston-valve distributes motive fluid to the piston-chamber A by means of inlet-ports 17 and 17^a, extending, respectively, from its valve-chamber D' to the opposite ends of the piston-chamber A and terminating in its valve-seat 18, and an exhaust-port 19, extending from its valve-chamber D' to a suitable exhaust-outlet 20 and likewise terminating in its valve-seat 18, Fig. 4, while the supplemental valve 80 E distributes motive fluid to the piston-valve chamber D', so as to reciprocate the piston-valve D and is reciprocated in turn by motive fluid distributed to its valve-chamber E' by the piston-valve D, such co-operation being effected by means of suitable ports connecting the two valve-chambers. 90

In carrying out my invention it is of course possible to vary within wide limits the arrangement and construction of the piston-valve, the supplemental valve, and the valve-chambers therefor. As illustrative of such possibilities of variation I have shown two different arrangements, which embody certain broader features in common, but which vary as to details of construction. One of these 100 arrangements is illustrated in Figs. 4 to 12, inclusive, and the other in Figs. 13 to 15, inclusive, of the drawings. I have chosen to incorporate in this application the claims for the broader features common to both arrangements and for specific construction illustrated in Figs. 4 to 12, inclusive, and to incorporate in another application, filed contemporaneously herewith, the claims for the specific construction illustrated in Figs. 13 to 15, inclusive. 105 110 115

Referring first to the construction illustrated in Figs. 4 to 12, inclusive, of the drawings, it will be observed that the supplemental-valve chamber E' is provided by an internal bore formed concentrically in the piston-valve D and adapted to contain the supplemental valve E and also that the piston-valve chamber D' is provided by a cylinder F and is connected with a supply-chamber 21, 120 which latter forms a continuation of and receives motive fluid from a main inlet-port 22. The piston-valve chamber D' is connected with the supply-chamber 21 by means of a couple of pairs of inlet supply-ports 23 24 125 and 23^a 24^a, which are formed in the wall separating said chambers from one another. In order to properly distribute motive fluid 130 within the piston-chamber by its reciproca-

tion, the piston-valve D is constructed with the upper and lower circumferentially-formed recesses 25 and 25^a and an intermediate similar recess 26, separated from the recesses 25 and 25^a by cylindrical heads 27 and 27^a, which said recesses 25, 25^a, and 26 are so arranged as to allow either the upper end of the piston-chamber to receive motive fluid from the upper supply-ports 23 and 24 by way of its upper 5 inlet-port 17 and the upper piston-valve recess 25 and the lower end of the piston-chamber to exhaust into the main exhaust-port 19 by way of its lower inlet-port 17^a and the intermediate piston-valve recess 26 when the 10 piston-valve is below a predetermined point in its stroke or to allow the lower end of the piston-chamber to receive motive fluid from the lower supply-ports 23^a and 24^a by way of its lower inlet-port 17^a and the lower piston- 15 valve recess 25^a and the upper end of the piston-chamber to exhaust into the main exhaust-port 19 by way of its upper inlet-port 17 and the intermediate piston-valve port 26 when the piston-valve D is above a predetermined point in its stroke. 20

It will be observed that the period of admission of motive fluid into the inlet-port 17 begins when the terminal opening of said port is first put into communication with the 25 piston-valve recess 25 by the passage of the upper edge of the cylindrical head 27 beyond the upper edge of said terminal opening during the downstroke of the piston-valve and that such period terminates when said terminal opening of the port 17 is finally shut off from communication with the piston-valve recess 25 by the arrival of said upper edge of the head 27 opposite said upper edge of the terminal opening of the port 17 on the return 30 upstroke of the piston-valve; also, that in a similar manner the period of admission of motive fluid into the lower piston-chamber inlet-port 17^a begins when the lower edge of the valve-head 27^a passes beyond the lower 35 edge of the terminal opening of said port 17^a on the upstroke of the valve and terminates when said lower valve-head edge arrives at said lower edge of the port-terminal on the downstroke of the valve. It will be further 40 observed that although said piston-valve D is free to move in its chamber D' the motive fluid passing thus in its circumferential recess exerts an equal pressure in both directions on the sides of such recesses, and 45 therefore fails to move the valve. The piston-valve D is reciprocated in its chamber D', so as to thus distribute motive fluid to the piston-chamber A by motive fluid which is first admitted to the supplemental-valve 50 chamber E' and is then discharged into and exhausted from the piston-valve chamber D' alternately on opposite sides of the piston-valve D, according as the supplemental valve E is at one or the other of the ends of its 55 stroke. To such end the piston-valve D is constructed with a couple of sets of radial ports 28 and 28^a, Fig. 11, extending, respec-

tively, between its upper recess 25 and the upper end of the supplemental-valve chamber E' and between its lower recess 25^a and the lower end of the supplemental-valve chamber E', whereby motive fluid can be admitted either to the upper or the lower end of the latter, according as the recess 25 is in communication with the ports 23 and 24 or the recess 25^a is 70 in communication with the ports 23^a and 24^a. Said piston-valve D is also constructed with an intermediate set of radial ports 29, Fig. 12, extending between its intermediate recess 26 and the longitudinal middle of the supplemental-valve chamber E', whereby motive fluid can exhaust from the middle of said chamber into the intermediate recess 26 and thence into the main exhaust-port 19, and is also constructed with a couple of longitudinally-arranged ports 30 and 30^a, extending, respectively, from one end of its ends to the end of the supplemental-valve chamber E' farthest removed therefrom, and having side openings 32 and 32^a, respectively, opening 80 into said chamber E', by which arrangement motive fluid admitted to one or the other of the ends of the supplemental-valve chamber can be admitted to the piston-valve chamber to the side of the piston-valve remote from 85 such end of the supplemental-valve chamber, and by which arrangement also motive fluid in the piston-valve chamber can be exhausted therefrom into the supplemental-valve chamber sufficiently near the longitudinal middle 90 portion thereof to allow it to pass into the intermediate recess 26. 95

The supplemental valve E is provided with a couple of circumferential recesses 33 and 33^a, formed by cylindrical valve-heads 35 and 36 and 35^a and 36^a, respectively, whereby motive fluid can pass from the radial ports 28 into the side opening 32^a of the longitudinal port 30 when said valve is at the lower end of its stroke, Fig. 9, and from the radial 105 ports 28^a into the side opening 32 of the port 30 when the valve is at the upper end of its stroke, and is provided also with a long intermediate recess 34, formed by the valve-heads 35 and 35^a, whereby motive fluid can 110 pass from the port 30 by way of its side opening 32 into the radial ports 29 when the valve is at the lower end of its stroke and from the port 30^a by way of its side opening 32^a into 115 said radial ports 29 when the valve is at the upper end of its stroke. By such arrangement when the supplemental valve is at the lower end of its stroke, as shown in Fig. 9, motive fluid passes from the ports 23 and 24 into the piston-valve chamber D' below the 120 piston-valve D by way of the piston-valve recess 25, radial ports 28, supplemental-valve recess 33, side opening 32^a of port 30^a, and port 30^a and operates to move the piston-valve upward, during which upward movement the upper end of the piston-valve chamber exhausts into the main exhaust-port 19 by way of the longitudinal port 30, the side opening 32 thereof, the intermediate supple- 125 130

mental-valve recess 34, the radial ports 29, and the intermediate piston-valve recess 26, and when the supplemental valve is at the upper end of its stroke motive fluid passes 5 from the ports 23^a and 24^a into the piston-valve chamber D' above the piston-valve by way of the piston-valve recess 25^a, radial ports 28^a thereof, supplemental-valve recess 33^a, side opening 32 of port 30, and port 30, 10 and operates to move the piston downward, during which downward movement motive fluid escapes from the lower end of the piston-valve chamber into the main exhaust-port 19 by way of longitudinal port 30^a, side 15 opening 32^a thereof, the intermediate supplemental-valve recess 34, radial ports 29, and the intermediate piston-valve recess 26, it being observed that the motive fluid passing thus in the recesses of the supplemental valve 20 exerts an equal pressure in both directions on said valve and so does not operate to move the same.

The supplemental valve E is reciprocated by motive fluid, which is admitted to and exhausted from the opposite ends of its chamber in alternation by the reciprocation of the piston-valve. To such end the piston-valve is provided near its ends with circumferential recesses 37 and 37^a, formed between cylindrical heads 39 and 39^a, respectively, and also with radial ports 38 and 38^a, Fig. 10, which latter extend, respectively, between the upper recess 37 and the upper end of the supplemental-valve chamber E' and between 35 the lower recess 37^a and the lower end of said valve-chamber E'. By such arrangement when the piston-valve has descended sufficiently to bring the recess 37 into communication with the supply-port 24 motive fluid 40 will be admitted to the upper end of the supplemental-valve chamber E' and will operate to drive the supplemental valve E downward, and when the piston-valve has descended sufficiently to bring the recess 37^a into communication with the supply-port 24^a motive fluid 45 will be admitted to the lower end of the supplemental-valve chamber E' and will operate to drive the supplemental valve upward. The recesses 37 and 37^a could be so situated 50 upon the piston-valve D as to allow motive fluid to enter one or the other of the ends of the supplemental-valve chamber, so as to actuate the supplemental valve and thereby cause a reversal of the piston-valve at any 55 desired time after motive fluid has begun to enter the corresponding end of the piston-chamber, it being observed that by thus delaying the entrance of motive fluid to the supplemental-valve chamber until a time 60 after it has begun to enter the piston-chamber the danger of causing a premature termination of the period of admission to the latter by a too sudden reversal of the piston-valve is avoided. As a preferred arrangement, however, said recesses 37 and 37^a are 65 so situated as to delay such entrance of motive fluid to the supplemental-valve chamber

until a time when the piston-valve has reached substantially one or the other of the ends of its stroke, as shown in Fig. 9, by which arrangement is procured the longest possible period of admission of motive fluid to the piston-chamber. 70

As a matter of further improvement in the arrangement for reciprocating the supplemental valve, the longitudinal piston-valve ports 30 and 30^a are extended beyond their side openings 32 and 32^a and are provided with end openings 31 and 31^a, respectively, which latter are so situated that during the 80 descent of the supplemental valve E the end opening 31^a is uncovered by the supplemental-valve head 36 at a time before the side opening 32^a is uncovered by the corresponding valve-head 35, and during the rise of the supplemental valve the end opening 31 is uncovered by the supplemental-valve head 36^a at a time before the side opening 32 is uncovered by the corresponding valve-head 35^a. 85 By such arrangement the motive fluid admitted primarily to one or the other of the ends of the supplemental-valve chamber for the purpose of actuating the supplemental valve is subsequently discharged by way of one or the other of the ports 30 and 30^a into 90 the opposite end of the piston-valve chamber at a time immediately preceding the arrival of the piston-valve at one or the other of the ends of its stroke, and thereby operates to cushion said valve against shock at the ends 95 of its strokes and also to insure its quick reversal. 100

As an arrangement for properly exhausting the supplemental-valve chamber during the movement of the supplemental valve, the piston-valve D is provided with longitudinally-formed exhaust-ports 40 and 40^a, having outer end openings 41 and 41^a and inner end openings 42 and 42^a, respectively, whereby motive fluid can pass from one or the other of the 105 ends of the supplemental-valve chamber into the intermediate recess 34 of said valve, as required by the movement of the valve. The outer ends 41 and 41^a of said exhaust-ports 40 and 40^a are desirably so situated as to be 110 closed by one or the other of the valve-heads 36 and 36^a at a time shortly before the arrival of the supplemental valve at the ends of its stroke, by which arrangement the escape of 115 motive fluid during exhaust is cut off by the supplemental valve at such times, and the remaining motive fluid is compressed, so as to form a cushion adapted to prevent shock to said valve at the ends of its stroke. The 120 result of such valve arrangement is that when the piston-valve descends to the lower end of its stroke, as shown in Fig. 9, motive fluid is admitted to the upper end of the supplemental-valve chamber and the supplemental valve descends, which descent of the supplemental valve operates to admit motive fluid to 125 the lower end of the piston-valve chamber and causes the piston-valve to rise, and when the piston-valve arrives at the upper end of 130

its stroke motive fluid is admitted to the lower end of the supplemental-valve chamber and the supplemental valve rises, which rise of the supplemental valve operates to admit motive fluid to the upper end of the piston-valve chamber and causes the piston-valve to descend, and so on, as before. This continuous and independent operation of the valve mechanism allows motive fluid to be admitted to the piston-chamber for a sufficiently-long period of time to properly actuate the piston, and also it occurs without jarring by reason of the fact that both of the valves are cushioned against shock at the ends of their strokes.

With reference to the construction of said piston-valve D and supplemental valve E and of the cylinder F, providing the piston-valve chamber D', the same can be conveniently constructed as follows: The piston-valve D can be constructed of a hollow exterior shell d, a hollow interior shell d', fitted tightly within the exterior shell d and having a bore adapted to form the chamber for the supplemental valve, and a couple of screw-threaded plugs or end pieces d² d², adapted to fit into the ends of the bore of the interior shell d'. The exterior shell d can have the requisite recesses 25 26 37, &c., formed in its exterior surface, and can also have additional recesses formed therein for the accommodation of packing-washers or the like, which are particularly well adapted to provide the cylindrical heads 27 27^a, &c. The inner cylindrical shell d' can have the longitudinal ports 30 and 30^a formed in its exterior surface before it is inserted within the exterior shell d, after which insertion the radial ports 28 29, &c., can be bored in both shells. Such construction is inexpensively and easily made and is particularly advantageous, in that it provides for the convenient formation of the longitudinal ports 30 and 30^a and the end and side openings 31, 32, 31^a, and 32^a thereof. The supplemental valve E can be constructed in suitable cylindrical form and can be provided with the requisite recesses and cylindrical heads, which latter can be provided with suitable packing-rings for making them tight against the leakage of motive fluid. The piston-valve cylinder F can be suitably constructed with a hollow extension F', adapted to provide the inlet-chamber 21, and can be provided with removable screw-threaded ends ff, whereby the piston-valve can be readily removed and replaced. Each pair of supply-ports 23 24 and 23^a 24^a could be replaced by a single port of substantially the width of the space between the farthest-removed walls of each pair; but the arrangement shown is preferred, as the packing-washers forming the heads 39 39^a cannot enter either of the small ports, whereas they might enter a large port and be injured or torn from their position. Such construction of valve mechanism can be easily constructed and can be operated economically and with little attendance and

repair or replacement of ports. Also the difficulty of forming ports in the valve-seat and the inconvenience of having ports which are inaccessible by reason of their being located in the valve-seat are avoided.

In the valve mechanism illustrated in Figs. 13 to 15, inclusive, of the drawings, the cylinder F, providing the piston-valve chamber D', is arranged intermediate of the piston-chamber A and the supplemental-valve chamber E', and the latter is provided by a separate cylinder G and communicates primarily with the inlet-port 22 formed in the front side of the cylinder G. The supplemental-valve chamber D' and the piston-valve chamber are connected by a couple of ports 23 and 23^a, so as to supply the latter with motive fluid for the piston-chamber. In order to distribute such motive fluid to the piston-chamber, the piston-valve D is constructed in a manner substantially similar to the piston-valve illustrated in the preceding arrangement—that is to say, said piston-valve is provided with circumferential recesses 25 and 25^a, formed by cylindrical heads 39 and 27 and 39^a and 27^a, respectively, which said recesses are adapted to allow motive fluid to pass from the upper supply-port 23 into the upper inlet-port 17 when the piston-valve is below a predetermined point in its stroke and to pass from the lower supply-port 23^a into the lower inlet-port 17^a when the piston-valve is above a predetermined point in its stroke. Also said piston-valve is provided with an intermediate circumferential recess 26, formed by the heads 27 and 27^a, which said recess 26 is adapted to allow the lower end of the piston-chamber to exhaust into the main exhaust-port 19 when said valve is below the lower predetermined point and to allow the upper end of the piston-chamber to exhaust into said main exhaust-port 19 when the valve is above the upper predetermined point.

The arrangement for reciprocating the piston-valve comprises ports 30 and 30^a, formed longitudinally in the wall H, separating the valve-chambers from one another and provided, respectively, with outer end openings 115 opening into the ends of the piston-valve chamber and with inner end openings 32 and 32^a, respectively, opening into said chamber near its longitudinal middle, and also with intermediate side openings 31 and 31^a, respectively, opening into the supplemental-valve chamber E'. By such arrangement the upper end of the piston-valve chamber can receive motive fluid from the supplemental-valve chamber by way of the side opening 31 and the outer end opening of the port 30 and the intermediate portion of said port 30, so as to drive the piston-valve downward, during which downward movement the lower end of the piston-valve chamber can exhaust into the main exhaust-port 19 by way of the port 30^a and its end openings and the intermediate piston-valve recess 26, and also the lower end of the piston-valve chamber can receive

motive fluid by way of the outer end opening of the port 30^a, the side opening 31^a thereof, and the intermediate portion of said port, so as to drive the piston-valve upward, during which upward movement the upper end of the piston-valve chamber can exhaust into the main exhaust-port 19 by way of the port 30 and its end openings and said intermediate recess 26. To such end the supplemental valve E is constructed with a circumferential recess 34 and a couple of end cylindrical heads 36 and 36^a, forming such recess 34, whereby when said valve is at the upper end of its stroke its recess 34 is in communication with the side opening 31 of the port 30, and its lower head 36^a closes the side opening 31^a of the port 30^a, and also when said valve is at the lower end of its stroke its recess 34 is in communication with said side opening 31^a, and its upper head 36 closes said side opening 31. The descent of the supplemental valve therefore causes the rise of the piston-valve, and, conversely, its rise causes the descent of said piston-valve. The arrangement for reciprocating the supplemental valve to such end comprises a couple of ports 38 and 38^a, extending longitudinally in said separating-wall H and having, respectively, outer end openings opening into the ends of the supplemental-valve chamber and inner end openings 38^b and 38^c, respectively, opening into the piston-valve chamber on opposite sides of its longitudinal middle. By such arrangement when the piston-valve D has risen sufficiently to place its lower recess 25^a into communication with the inner end opening 38^c of the port 38^a motive fluid passes from said recess into the lower end of supplemental-valve chamber and drives the supplemental valve upward, during which upward movement of said valve the upper end of its chamber exhausts, by way of the port 38, into the intermediate piston-valve recess 26, and thence into the main exhaust-port 19, and also when the piston-valve has descended sufficiently to place its upper recess 25 into communication with the end opening 38^b of the port 38 motive fluid passes from said recess into the upper end of the supplemental-valve chamber and drives said supplemental valve downward, during which downward movement of said valve the lower end of its chamber exhausts, by way of the port 38^a, into said recess 26 and thence into said exhaust-port 19. The inner end openings 38^b and 38^c of said ports 38 and 38^a could be so situated as to admit motive fluid to the supplemental-valve chamber at any desired time after the same has been admitted to the piston-chamber; but as a preferred arrangement said end openings 38^b and 38^c are so situated as to admit motive fluid to the supplemental-valve chamber only at a time when the piston-valve arrives at one or the other of the ends of its stroke. The operation of this latter valve arrangement is similar to that of the preceding arrangement—that is to say,

when the piston-valve descends to the lower end of its stroke motive fluid is admitted to the upper end of the supplemental-valve chamber and the supplemental valve descends, which descent of the supplemental valve operates to admit motive fluid to the lower end of the piston-valve chamber and causes the piston-valve to rise, and when the piston-valve arrives at the upper end of its stroke, as shown in Fig. 13, motive fluid is admitted to the lower end of the supplemental-valve chamber and the supplemental valve rises, which rise of the supplemental valve operates to admit motive fluid to the upper end of the piston-valve chamber and causes the piston-valve to descend, and so on, as before. With reference to the construction of this latter valve arrangement the valves D and E are conveniently and inexpensively constructed of properly-recessed cylinders, while the cylinders F and G, providing the valve-chambers D' and E', respectively, are suitably constructed in cylindrical form and are desirably provided with detachable ends f f and g g, respectively, whereby said valves can be easily removed and replaced. The wall H, separating the valve-chambers D' and E' from one another, is conveniently provided by the adjacent sides of the cylinders F and G, which said sides are accordingly provided in any suitable manner with the requisite ports. As a preferred arrangement the ports 38 and 38^a are conveniently formed in the bottom of the cylinder G, Fig. 15, before the same is attached in position to the cylinder F, and in order to avoid interference with the ports 23 and 23^a and the side openings 31 and 31^a of the ports 30 and 30^a said ports 38 and 38^a are constructed with loop portions 38^d and 38^e, respectively, which severally encircle one of said ports 23 and 23^a and one of said side openings 31 and 31^a; also, the longitudinal ports 30 and 30^a are constructed with loop portions 30^b and 30^c, respectively, which severally encircle one of said ports 23 and 23^a and one of the inner end openings 38^b and 38^c of the ports 38 and 38^a.

With reference to the common features of the two valve arrangements it will be observed that in both of the same the sets of ports leading to the piston-chamber and to the supplemental-valve chamber, respectively, and controlled by the piston-valve for distributing motive fluid to said chamber have separate terminal openings in the piston-valve chamber, which said openings are so situated as to admit motive fluid to the piston-chamber before and for a greater length of time than the same is admitted to the supplemental-valve chamber, and also that as a preferred arrangement motive fluid is admitted to the supplemental valve chamber only at a time when the piston-valve arrives at one or the other of the ends of its stroke.

In order to prevent an undesirable shock on the part of the piston arrangement upon the arrival of the same at the ends of its

stroke, the inlet-ports 17 and 17^a are provided with side openings 17^b and 17^c, respectively, which said side openings are situated at short distances from the ends of the piston-chamber and are adapted to be closed by the piston-heads B and B', respectively, when said piston-heads approach one or the other of the ends of their stroke. Said ports 17 and 17^a are also provided at their ends with spring-controlled check-valves 45 and 45^a, respectively, which said check-valves are arranged to open outwardly from the end of said ports 17 and 17^a, so as to allow the passage of motive fluid from the latter into the piston-chamber, but to prevent its passage from the piston-chamber back into said ports. By such arrangement the escape of motive fluid exhausting from the ends of the piston-chamber as the piston-heads approach one or the other of the ends of their strokes is prevented and the motive fluid so confined against escapement is compressed by the further progression of the piston arrangement, so as to form an elastic abutment acting in opposition to such further progression and providing at the same time a high initial pressure for the return stroke of said piston arrangement.

With reference to the construction of the cylinder A', which provides the piston-chamber A, said cylinder A' is constructed with a rear extension A² for attachment to a suitable support and is desirably provided with a detachable upper end piece 46 and a detachable stuffing-box 47 for the piston-rod at its lower end. The stuffing-box 47 could be constructed in any suitable manner; but as a matter of further improvement it is constructed of a single piece, whereby it is always tight against leakage of the motive fluid and also whereby is avoided the employment of nuts and bolts, which would be necessary for securing its parts together should it be constructed of two or more pieces. The said stuffing-box 47 is provided with a suitable bore for the packing-glands, which said bore is desirably of greater diameter than the diameter of the piston-heads B and B', whereby when it is desired to remove said piston-heads from the piston-chamber for any purpose they can be withdrawn through the stuffing-box without detaching the latter. Said stuffing-box incloses a couple of packing-glands 48 and 49, which occupy the upper and lower ends, respectively, of its bore, and it incloses also a suitable bundle of packing confined between said glands. The upper packing-gland 48 is capable of easy insertion in and removal from the upper end of the stuffing-box 47 when the said stuffing-box is detached from the piston-cylinder, and when so inserted within said upper end fits against the lower end of the piston-cylinder, it being observed that the diameter of the packing-gland 48, being substantially the same as that of the bore of the stuffing-box 47, is greater than that of the bore of the piston-cylinder, and that said gland therefore is prevented from entering

the bore of the piston-cylinder by reason of its greater diameter, but abuts against the lower end of said cylinder. The lower packing-gland 49 screws into and out of said stuffing-box 47 for the adjustment of the packing confined between the two glands by way of corresponding screw-threads with which it and the lower end of the packing-box are provided. Said packing-glands 48 and 49 are each desirably constructed of two longitudinal halves, so as to permit of their being easily removed from and replaced upon the piston-rod without necessitating the detachment of either the piston-heads or the drill attachment.

The end piece 46 of the piston-cylinder and the stuffing-box 47 for the piston-rod could be detachably secured to said cylinder in any preferred manner. As a matter of further improvement, however, both the end piece and the stuffing-box are secured to the cylinder by a number of long rods 50, which extend the entire length of said cylinder and pass through suitable flanges formed at the ends of the cylinder and of the stuffing-box, respectively, and which are held in place by means of suitable nuts fitted upon their screw-threaded ends. By such arrangement the employment of an undesirably large number of bolts and nuts for securing the end piece and the stuffing-box to the ends of the piston-cylinder is dispensed with, and also the said end piece and stuffing-box can be tightened up by the adjustment of a single set of nuts.

What I claim is—

1. The combination with a piston and a ported piston-chamber therefor, of a fluid-actuated reciprocating piston-valve for distributing motive fluid to the piston-chamber, and a fluid-actuated reciprocating supplemental valve, said valves being arranged to distribute motive fluid for reciprocating one another, and the piston-valve being arranged to admit motive fluid to the supplemental-valve chamber for actuating the supplemental valve at a time after it has admitted the same to the piston-chamber for actuating the piston, as set forth.

2. The combination, with a piston and a ported piston-chamber therefor, of a fluid-actuated reciprocating valve for distributing motive fluid to the piston-chamber, and a fluid-actuated reciprocating supplemental valve, said valves being arranged to distribute motive fluid for reciprocating one another, and the piston-valve being arranged to admit motive fluid for actuating the supplemental valve at a time after it has admitted the same to the piston-chamber for actuating the piston and when it has arrived at one or the other of the ends of its stroke, as set forth.

3. The combination with a piston and a ported piston-chamber therefor, of a fluid-actuated reciprocating piston-valve for distributing motive fluid to the piston-chamber, and a fluid-actuated reciprocating supple-

mental valve, said valves being arranged to distribute motive fluid for reciprocating one another, and the piston-valve being arranged to admit motive fluid for actuating the piston for a longer period of time than for actuating the supplemental valve, as set forth.

4. An impact-tool having a reciprocating piston operated by means of a fluid-actuated reciprocating valve which distributes motive fluid to the piston-chamber and a fluid-actuated reciprocating supplemental valve arranged for distributing motive fluid for reciprocating the piston-valve, and reciprocated by motive fluid distributed to it by the piston-valve; and constructed with ports extending from both the piston-chamber and the supplemental-valve chamber to the piston-valve chamber, and having separate terminal openings in the latter, as set forth.

5. The combination, with the piston and ported piston-chamber therefor, of a fluid-actuated reciprocating piston-valve for distributing motive fluid to the piston-chamber, and a fluid-actuated reciprocating supplemental valve inclosed in a chamber formed interiorly in said piston-valve, said valves being arranged for distributing motive fluid for reciprocating one another, as set forth.

6. The combination, with the piston and ported piston-chamber therefor, of a fluid-actuated reciprocating piston-valve for distributing motive fluid to the piston-chamber, and a fluid-actuated reciprocating supplemental valve inclosed in a chamber formed interiorly in said piston-valve, said valves being arranged for distributing motive fluid for reciprocating one another, and the piston-valve being arranged to admit motive fluid to the piston-chamber at a time before it admits the same to the supplemental-valve chamber, as set forth.

7. The combination with the piston and ported cylinder therefor, of a fluid-actuated reciprocating piston-valve for distributing motive fluid to the piston-chamber, and a fluid-actuated reciprocating supplemental valve confined in a chamber formed interiorly in the piston-valve, said piston-valve being provided with ports arranged to admit motive fluid to one or the other of its ends when the supplemental valve is at a corresponding end of its valve-chamber, and also with inwardly-extending ports adapted to conduct motive fluid to one or the other of the ends of said interior chamber, and being inclosed in a valve-chamber having ports arranged to communicate with one or the other of said inwardly-extending ports according as the piston-valve is at one or the other of the ends of its stroke so as to admit motive fluid to the end of the supplemental-valve chamber at which the supplemental valve is situated, substantially as set forth.

8. The combination with the fluid-actuated reciprocating supplemental valve, of the reciprocating piston-valve constructed with an interior chamber in which said supplemental

valve is confined, and provided with exhaust-ports having openings adapted to be closed by the supplemental valve at a time before 70 said supplemental valve has reached the ends of its strokes whereby the same is cushioned against shock as set forth.

9. The combination with the reciprocating supplemental valve, of the reciprocating fluid-actuated piston-valve constructed with an interior valve-chamber in which said supplemental valve is confined, and provided with inlet-ports adapted to conduct motive fluid from the supplemental-valve chamber into 80 its chamber to one or the other of its ends, according as the supplemental valve is at one or the other of the ends of its stroke and provided with additional openings arranged to be uncovered by said supplemental valve before the same has reached the ends of its stroke, whereby the piston-valve is cushioned against shock, substantially as set forth.

10. In an impact-tool, the combination of the piston comprising a couple of separated piston-heads, and a connecting-rod connecting the same; and an intermittently-twisting device arranged within the piston-chamber and engaging the connecting-rod intermediate of the piston-heads, substantially as 95 and for the purpose set forth.

11. In an impact-tool, the combination of the piston comprising a couple of separated piston-heads and a spirally-grooved connecting-rod attached to the same; and an intermittently-twisting device engaging the connecting-rod intermediate of the piston-heads and comprising a fixed collar provided with 100 engaging portions and fitted loosely over the connecting-rod, a loose collar provided with 105 corresponding engaging portions and also with inwardly-projecting tongues adapted to engage the spiral grooves of the connecting-rod, and having a friction connection with the latter, and a stop for limiting the movement of the loose collar longitudinally of the piston-chamber, substantially as set forth.

12. In an impact-tool, the combination with a couple of separated piston-heads and a spirally-grooved connecting-rod attached thereto, of a fixed collar provided with engaging portions and fitted loosely over the connecting-rod; a loose collar provided with corresponding engaging portions and also with inwardly-projecting tongues adapted to engage 115 the spiral grooves of the connecting-rod; a friction-ring inclosing the connecting-rod and confined in an annular chamber in the loose collar; and a sleeve in which said collars are inclosed, said sleeve being fitted within the 120 piston-chamber and being constructed with an inwardly-projecting flange adapted to form a stop to limit the movement of the loose collar longitudinally of the piston-chamber, substantially as described.

13. In an impact-tool, the combination of a spirally-grooved reciprocating rod connected with the implement for reciprocating the same; and an intermittently-twisting device

comprising a fixed toothed collar fitted loosely over the reciprocating rod, a corresponding toothed loose collar having a friction connection with said rod and provided with inwardly-projecting teeth for engaging the spiral groove thereof, and a stop adapted to limit the movement of said loose collar in a direc-

tion longitudinally of the reciprocating rod, as set forth.
